REFRIGERATOR WITH A TOP ICE BOX

Carl J. Wagner, Detroit, Mich.

Application July 15, 1946, Serial No. 683,585

3 Claims. (Cl. 62—46)

1

The present invention relates to a combination ice and mechanical refrigerator particularly adapted for use in house trailers. The refrigerator is provided with an electric power mechanical refrigerating unit and also provides space for the reception of a block of ice when power is not available for the electric motor.

It is an object of the present invention to provide an increased circulation of air through the cooling compartment of a refrigerator. It is a further object of the present invention to prevent a secondary circulation of air limited to the food storage compartment of a refrigerator. It is a further object of the present invention to prevent condensation on the upper wall of a food storage compartment and consequent dripping of moisture on those articles stored in the food storage compartment. It is a further object of the present invention to provide for increased efficiency of air flow in a refrigerator having a mechanical refrigerating unit and having space for the reception of a block of ice.

It is a feature of the present invention to provide a refrigerator having an inclined air flow controlling partition separating the interior of the refrigerator into an upper cooling compartment and a lower food storage compartment, the upper and lower edges of said partition being spaced from the adjacent inner walls of the refrigerator. It is a further feature of the present invention to provide an inclined air flow controlling partition of the type referred to above, in which the partition is insulated to maintain its lower surface at substantially the same temperature as the other walls of the food storage compartment.

It is a further feature of the present invention to provide an inclined air flow controlling partition in a refrigerator adapted to divide the interior thereof into an upper cooling compartment and a lower food storage compartment, in which a mechanical refrigerating unit is positioned at one side of the cooling compartment and means are provided for alternatively supporting a block of ice at the other side of the cooling compartment, the partition being inclined downwardly and inwardly from its lateral edges.

Other objects and features of the invention will become apparent as the description proceeds, especially when taken in conjunction with the accompanying drawings, wherein:

Figure 1 is a front elevation of a refrigerator embodying the present invention in which the

door of the refrigerator has been removed to disclose the interior arrangement;

Figure 2 is a vertical section on the line 2—2 of Figure 1;

Figure 3 is a horizontal section on the line 3—3 of Figure 2;

Figure 4 is a fragmentary section on the line 4—4 of Figure 3;

Figure 5 is a fragmentary section on the line 5—5 of Figure 3;

Figure 6 is a fragmentary section on the line 6—6 of Figure 3 looking in the plane of the partition; and

Figure 7 is a fragmentary transverse section 15 of the partition member.

Referring first to the complete assembly illustrated in Figures 1, 2 and 3, there is illustrated a refrigerator 10 having a cabinet providing a lower space 11 for the reception of an electric motor and operating parts of a mechanical refrigerator. The cabinet provides a box-like space indicated generally at 12 which is separated by an inclined partition 13 into an upper cooling compartment 14 and a lower food storage compartment 15.

The lower food storage compartment 15 is provided with the usual horizontal supporting shelves 16 and in addition there is provided a drain pipe 17 passing through the lower wall of the food storage compartment 15 for the purpose of carrying away water resulting from the melting of ice when ice is employed in the cooling compartment.

For clearness in these views the door of the box-like space 12 has been omitted, but it will be understood that this door comprises the usual heavily insulated door employed with present day refrigerators.

As best seen in Figure 1, the upper cooling compartment 14 is provided with an evaporator housing 18 which may be of conventional design and will provide space for ice cube trays. The evaporator housing as illustrated is located at one side of the cooling compartment and leaves a substantial space in the other side thereof for the reception of a block of ice indicated in dotted lines at 18'. A horizontal ice supporting shelf 19 is provided and is shown as formed of wire elements so as to expose all sides of the ice to the air in the cooling compartment for the purpose of increasing the cooling effect of the ice.

The inclined partition 13 serves a plurality of functions and is especially designed to improve the efficiency with which these functions are carried out. As best seen in Figures 4 and

7, the partition 13 is formed of an upper metallic plate 20 and a lower metallic plate 21, these plates being spaced apart a substantial distance and having suitable insulating material indicated at 22 provided therebetween.

One of the functions of the partition 13 is to serve as a drip pan for intercepting the water resulting from melting of the ice when ice is employed in the cooling compartment. For this purpose the upper surface of the partition 13 is inclined inwardly from its lateral edges at an angle designated 23, as best seen in Figure 4. In addition, the lower edge of the partition 13 is provided with a spout 24 at its central portion and the rear edge of the partition is provided with a raised bead 25 at either side of the spout 24 to restrict the flow of water to the spout 24. As indicated in Figures 4 and 7, the bead extends completely around the partition 13. It will be understood that the spout 24 overlies the upper end of the drain pipe 17 so that water formed by the melting of the ice is caused to flow out of the refrigerator through the drain pipe.

The partition 13 is supported from the inner walls of the refrigerator by means of screws 26, as best seen in Figure 4, the upper plate 20 having down turned flanges at the sides of the partition, as best seen in Figure 7, these flanges being provided with slots indicated at 27 to be engaged over the screws 26. This assembly provides for ready removal of the partition when desired.

Extending forwardly from the rear wall of the cooling compartment is an apron 30. The apron 30 may extend completely across the back of the refrigerator, but at all events it extends completely across that portion thereof which is adapted to receive a block of ice. The forward edge of the apron 30 overlies the rear edge of the partition 13 so that water intercepted by the apron 30 drops off its forward edge onto the partition 13 adjacent its rear edge.

As best seen in Figure 2, the partition 13 is mounted in the refrigerator so that it is inclined downwardly and rearwardly at a substantial angle. This angle may be between 5° and 10° and is preferably in the neighborhood of 7° from the horizontal. This inclination of the partition 13 serves a dual purpose. In the first place, it provides for flow of water deposited therein from melting ice toward the rear end where it passes over the spout 24 and hence out the drain pipe 17.

More important, however, is its function in controlling the flow of air in the refrigerator. Cooled air is caused to flow by the inclination of the partition downwardly at the rear of the refrigerator and upwardly at the front thereof, as indicated by arrows in Figure 2. The front and rear edges of the partition 13 are spaced a substantial distance from the inner surface of the door and from the inner surface of the back wall of the refrigerator, respectively, so as to permit a substantial flow of air through the spaces defined thereby.

By providing substantial insulation between the upper and lower surfaces of the partition 13 two important additional advantages are achieved. In the first place, the provision of this insulation maintains the lower surface of the partition 13 at substantially the same temperature as the other walls of the food storage compartment. It will be appreciated that in the absence of such insulation the upper wall of the food storage compartment would be maintained at a relatively lower temperature, either by direct conduction from the cooler air in the cooling compartment

or by dropping of water resulting from melting ice thereon. This would have the effect of providing a surface at the top of the food storage compartment on which moisture would tend to condense and the condensate would then drip downwardly upon food in the food storage compartment, since the temperature of the partition would not be sufficiently low to freeze the moisture deposited thereon. This undesirable effect is completely avoided by the provision of the substantial insulation referred to.

A secondary undesirable effect is also avoided by the provision of the insulation which maintains the lower surface of the partition 13 at substantially the same temperature as the other walls of the food storage compartment. This secondary undesirable effect which is avoided is a restricted circulation of air within the food storage compartment itself. It will be appreciated that if the lower surface of the partition 13 were relatively colder than the other walls of the food storage compartment, air passing downwardly at the rear of the food storage compartment would then circulate upwardly at the front of the icebox and certain of this air would strike the lower surface of the partition and would thereby be cooled and would set up a restricted circulation in the food storage compartment so that the amount of air passing upwardly from the food storage compartment to the cooling compartment would be seriously reduced.

It was previously mentioned that the partition 13 is shaped so that its upper surface is inclined downwardly from the side edges thereof toward the center thereof. This causes the water dripping from the melting ice to flow to the center thereof and thence out the spout 24. It also has a further advantage in that it tends to distribute cool air, as will now be pointed out. It was stated at the outset that the cooling compartment was provided with a mechanical refrigerating unit or ice cooling means as circumstances required. The arrangement is such that when the mechanical refrigerating unit is in use the cooling effect thereof is located at one side of the cooling compartment. In like manner, when ice is relied upon for cooling, the cooling thereof is effective only in the other side of the cooling compartment. By providing a partition which inclines downwardly from its side edges, air which is cooled by either of the cooling agencies alternatively employed is directed not only toward the rear of the icebox but also toward the central portion thereof.

It will be appreciated that the provision of the inclined insulated partition greatly augments the air flow from the cooling compartment downwardly at its rear portion to the food storage compartment, which in turn forces relatively warmer air upwardly from the forward edge of the food storage compartment to the forward portion of the cooling compartment, and that as previously described the provision of the insulating means minimizes the setting up of a secondary circulation solely within the food storage compartment.

It will therefore be seen that the present construction provides a very efficient combination ice and mechanical refrigerator in which the cooling effect of the particular cooling agency employed is substantially augmented by the controlled flow of air in the refrigerator.

While I have illustrated and described a particular embodiment of my improved combination ice and mechanical refrigerator, it will be under-

stood that this has been done solely to enable those skilled in the art to practice the invention, the scope of which is indicated by the appended claims.

What I claim as my invention is:

1. A combination ice mechanical refrigerator comprising a box having an open front, a door closing said open front, a cooling compartment at the top of said box, a mechanical cooling unit at one side of said compartment, a member for supporting ice at the other side of said compartment, air flow controlling means dividing the interior of said box into said cooling compartment and a lower food storage compartment comprising a plate spaced from the rear wall of said box and the door thereof, said plate being transversely inclined downwardly and inwardly from the side edges thereof to direct downwardly moving cold air from either side of said cooling compartment toward the center of the box, said plate being downwardly and rearwardly inclined from the front edge thereof to direct cooled air rearwardly of the box, and a ledge extending forwardly from the rear wall of said box at the bottom of said cooling compartment effective to direct downwardly moving cold air from said cooling compartment onto said plate.

2. A combination ice mechanical refrigerator comprising a box having an open front, a door closing said open front, a cooling compartment at the top of said box, a mechanical cooling unit at one side of said compartment, a member for supporting ice at the other side of said compartment, air flow controlling means dividing the interior of said box into said cooling compartment and a lower food storage compartment comprising a plate spaced from the rear wall of said box and the door thereof, said plate being transversely inclined downwardly and inwardly from the side edges thereof to direct downwardly moving cold air from either side of said cooling compartment toward the center of the box, said plate being downwardly and rearwardly inclined from the front edge thereof to direct cooled air rearwardly of the box, and a ledge extending forwardly from the rear wall of said box at the bottom of said cooling compartment effective to direct down-

wardly moving cold air from said cooling compartment onto said plate, said plate serving also as a drip pan and having a pouring spout at its rear edge centrally thereof.

5 3. A combination ice mechanical refrigerator comprising a box having an open front, a door closing said open front, a cooling compartment at the top of said box, a mechanical cooling unit at one side of said compartment, a member for supporting ice at the other side of said compartment, air flow controlling means dividing the interior of said box into said cooling compartment and a lower food storage compartment comprising a plate spaced from the rear wall of said box and the door thereof, said plate being transversely inclined downwardly and inwardly from the side edges thereof to direct downwardly moving cold air from either side of said cooling compartment toward the center of the box, said plate being downwardly and rearwardly inclined from the front edge thereof to direct cooled air rearwardly of the box, and a ledge extending forwardly from the rear wall of said box at the bottom of said cooling compartment effective to direct downwardly moving cold air from said cooling compartment onto said plate, said plate serving also as a drip pan and having a pouring spout at its rear edge centrally thereof and a drain pipe located to receive water from melted ice below said spout.
